UNITED STATES PATENT OFFICE.

NAPOLEON B. HIEATT AND EDWIN R. HEARN, OF JERSEY CITY, NEW JERSEY

MACHINE FOR TAGGING PLUG-TOBACCO.

SPECIFICATION forming part of Letters Patent No. 269,788, dated December 26, 1882.

Application filed October 21, 1882. (No model.)

To all whom it may concern:

Be it known that we, N. B. HIEATT and EDWIN R. HEARN, of Jersey City, in the county of Hudson, in the State of New Jersey, have 5 invented certain new and useful Improvements in Machines for Tagging Plug - Tobacco, of which the following is a specification.

The invention is of a class adapted to attach a series of small independent tags of metal or 10 other suitable material in a row extending along one of the faces of the plug, and also to attach a long piece of tin-foil or analogous material, termed a "ribbon," to lie between the tags and the tobacco. The tags have claws, 15 which, being pressed into the tobacco, attach themselves and also the ribbon. By making the ribbon adhesive, with gum-arabic or other suitable material, the ribbon can be made to adhere directly to the tobacco, in addition to 20 the fastening effected by the small tags, provided the ribbon can be pressed properly against the tobacco, while its surface is adhesive in the act of tagging. Our machine presses the entire ribbon firmly against the tobacco in 25 the act of affixing it. A series of equidistant posts are planted in a fixed base. A ribbon-piece, of a length and breadth corresponding to a ribbon, is bored with holes corresponding to the posts, and fitted loosely thereon. A moving 30 platform is fitted loosely around this ribbon-piece and held up by gentle springs, lifting the ribbon-piece with it. When the parts are up, the top of the ribbon - piece is a little below the top of the platform and a little 35 above the tops of the several posts. When, after placing the tags and the properly-gummed ribbon in position, a plug of tobacco is placed on the platform and depressed, stops arrest the descent of the ribbon-piece, and other stops 40 arrest the descent of the platform; but the stops for the platform act later, so that when the tobacco is fully depressed the upper surface of the three parts--the platform, the ribbon-piece, and the posts--are all brought even, 45 and the tags and all parts of the ribbon are pressed firmly up against the tobacco. When the parts are allowed to rise again, the ribbon-piece is liable to jam in the platform, and to tend to be lifted therewith to too great a height. 50 We provide stops, which arrest the ascent of the ribbon - piece at the right point under all

circumstances. These stops also perform an important function in preventing the ribbon-piece from falling out when the machine is reversed for cleaning or for any other purpose. 55

The accompanying drawings form a part of this specification, and represent what we consider the best means of carrying out the invention.

Figure 1 is a plan view. Fig. 2 is a longitudinal section on the line R R in Fig. 1. This shows the machine with the parts in the elevated condition. A plug of tobacco is indicated in position ready to be depressed and receive the ribbon and tags. The remaining 60 figures are cross-sections, showing the machine in two conditions. Figs. 3 and 4 are sections on the line S S in Figs. 1 and 2. Fig. 3 shows the parts in the elevated condition, in which they receive the tags and ribbon, and Fig. 4 shows them in the depressed condition, into 70 which they are brought in the act of tagging. Figs. 5 and 6 are sections on the line T T in Figs. 1 and 2. Fig. 5 shows the parts in the elevated position, and Fig. 6 in the depressed. 75

Similar letters of reference indicate like parts in all the figures.

A is the foundation or base board, and a a are a series of posts equally spaced thereon.

D is the movable platform, formed with a 80 slot corresponding in width to the width of the ribbons to be applied, and of a length a little greater than such ribbons. Cross - pieces b, screwed or otherwise fixed on the lower face of the platform B, extend across the bottom of 85 the slot and support a ribbon-piece, E, of wood or other suitable material. This ribbon-piece E is of a little less thickness than the platform, and is provided with holes, which match loosely upon the posts a.

The uprights A' A² are planted in the ends of the base, and are received in recesses in the ends of the platform, so that they aid in guiding the latter. These posts support cross - pieces a' a², which prevent the platform from 90 rising too high.

C are springs, abutting on the base A, and pressing upward against the cross-pieces b, so as to lift the cross-pieces b with the platform B and the loose ribbon-piece E with gentle 100 force. The springs C force the platform up until it is arrested by the stops a' a².

B' is a gage, standing along the edge of the platform B.

B² is a removable piece, secured by fastenings adapted to allow its removal when desired to tag wider plugs of tobacco.

B³ is an end-gage, secured to the platform B by screws B⁴, standing in slots in the gage. This may be adjusted to the right and left with any degree of nicety. This serves to gage the position of the plug of tobacco longitudinally. It also gages the position of the ribbon.

Transverse pieces of board D stand on edge on the base A, and perform important functions. Certain portions of each are designated by additional marks of reference, as D'¹ D² D³. The surface D' is highest, and supports a fixed table, G. The surface D² is lower, and serves as a stop to arrest the descent of the ribbon-piece E. The surfaces D³ D³ are lower still, and serve as stops to arrest the descent of the movable platform B. In each upright board D, under the surfaces D², we bore a vertical hole. The upper part of this hole is of less diameter than the lower part. In the ribbon-piece E are set two screws, e. The shank of each screw is received loosely in the small portion, and the bead is received in the large portion of such hole. Each screw is adjusted so that its head comes to a bearing against the surface D⁴ when the movable platform B and the ribbon-piece E have risen to their full proper height. The surfaces D⁴, acting against the heads of the screws e, serve as stops to prevent the ribbon-piece E from either falling out when the machine is reversed, or from being carried up too far by any slight adhesion to the platform.

M is the tobacco, m the ribbon, and N the independent tags.

To operate the machine, the tags N are placed face downward, one on the top of each post a. Then the ribbon m, previously coated on its back with gum-arabic or other suitable adhesive material, is placed face downward on the ribbon-piece E. Then the plug of tobacco M is applied in the proper position, resting on the movable platform B each side of the ribbon-piece, and is pressed by the operator strongly downward. The first effect is to depress both B and E. Soon the ribbon-piece E is arrested by its stops D², but the tobacco and the platform continue to move downward. When the platform is finally arrested by its stops D³ the upper surface of the platform B, ribbon-piece E, and posts a are all even.

In this condition the ribbon-piece E presses the ribbon firmly against the tobacco, and the posts press the several independent tags firmly against the ribbon, and force their claws through the ribbon into the tobacco. It follows that

the ribbon m and the independent tags N are firmly attached to the tobacco M. On again lifting the plug of tobacco the parts rise again by the action of the springs C to their original positions. Toward the close of the rising motion the strip E is arrested by the contact of the heads of the screws e with the surfaces D⁴, and the platform B is arrested by the transverse pieces a' a². In case there has been any slight adhesion between the sides of the ribbon-piece E and the adjacent surfaces of the platform sufficient to overcome its gravity and prevent it from dropping, so as to bring its upper surface to the proper extent below the upper surface of the platform, the contact of the screw-heads against the surfaces or stops D⁴ will occur earlier, and will overcome the adhesion and hold the ribbon-piece E in its proper position, while the platform will continue to rise by the force of its springs C and compel the proper relation of the parts ready to receive the ribbon. This insures its proper position without requiring it to be depressed by the fingers under any circumstances.

Modifications may be made in the details. Parts of the invention can be used without the whole. We can employ a greater or less number of posts a, taking care that they should be always properly spaced, and that the ribbon-piece E should be correspondingly formed. We prefer that the springs C shall be each coiled around a post, a; but this is not absolutely necessary.

We claim as our invention—

1. In a machine for tagging plug-tobacco, the movable platform B b, ribbon-piece E, and posts a, in combination with each other and with the stops D², arranged to arrest the descent of the ribbon-piece E before the platform comes to rest and to press the ribbon firmly against the tobacco when the machine is worked, substantially as herein specified.

2. In a machine for tagging plug-tobacco, the movable platform B b, ribbon-piece E, and posts a, in combination with each other and with the stops D² to arrest the descent of the strip E, and with the stops D⁴ e to arrest the ascent of the strip E, arranged for joint operation, substantially as and for the purposes herein specified.

In testimony whereof we have hereunto set our hands at Jersey City, New Jersey, this 19th day of October, 1882, in the presence of two subscribing witnesses.
